United States Patent Office.

GEORGE ROTH, OF NEW YORK, N. Y., ASSIGNOR TO HEINEMANN AND SILBERMANN, OF SAME PLACE.

Letters Patent No. 95,145, dated September 21, 1869.

IMPROVEMENT IN LOOM FOR MAKING FRINGE.

The Schedule referred to in these Letters Patent and making part of the same.

To all whom it may concern:

Be it known that I, GEORGE ROTH, of the city and State of New York, have invented, made, and applied to use, a new and useful Improvement in Looms for Bullion-Fringes; and I do hereby declare the following to be a full, clear, and exact description of the said invention, reference being had to the annexed drawing, making part of this specification, wherein—

Figure 1 is a side view of the loom, with the lay near the extreme backward movement;

Figure 2 is a plan of the loom below the line $z z$, fig. 1;

Figure 3 is a rear view of the stop-motion for the bullion-hook; and

Figure 4 is a section of the lay and slide, and an elevation of the stop-motion for the hook.

Similar marks of reference denote the same parts.

This invention is devised for weaving and twisting bullion-fringe. Looms have before been made to effect this, but they are more complicated and liable to get out of order.

My loom is shown as made to weave one piece of fringe, but by multiplying the number of twisting-hooks and their actuating-gears, the loom may be made to weave several pieces of fringe at the same time, similarly to the weaving of tapes.

The weaving of the head of the fringe is similar to that of any ordinary weaving. The cord to be twisted to form the bullion is drawn in by a hook that is revolved after the shed is changed, and then stopped by peculiar mechanism, and the bullion unhooked by a finger actuated by a bent lever.

In twisting the bullion, the twist is liable to extend up into the woven head, and mar its flat appearance. This has heretofore been prevented by wires that are liable to become misplaced or injure the fabric.

I introduce in the reed and heddles three or more heavy threads or fine cords, which, being woven with the head, at the edge thereof, prevent the twist extending up into the woven ornamental heads, and after the fringe is complete these threads are cut and pulled out.

In the drawing—

a represents the frame of the loom.

b, the lay, hung to swing from above, and moved by the cranks *c d* and connecting-rods *c' d'* from the main shaft *e*, or in any other convenient manner.

e' is the gearing that is employed to actuate the heddles *f* through an upper rock-shaft; and at *f'* is the gearing forming the take-up motion to the roller *g*, upon which the fringe is wound.

g' is the breast-beam, and *2*, the sustaining-loop or roller, around which the fringe passes to the roller *g*.

These parts, heretofore described, being of known construction, and forming no part of my invention, require no further description.

The cord that forms the bullion, passes from the spool *h*, to which a friction-detention is applied, and is led through the eye *k* that is formed in a wire that is projected upward to a spring, *3*, and passes down to the treadle *l* that is operated by the cam *l*, so as to raise the bullion-cord as the hook *i* is moved endwise through the shed, and then the eye *k* descends to lay the said cord upon the shank of the hook, so that the hook takes said cord, and draws it through the shed by an end movement given to the same, and then the hook *i* is revolved to twist the bullion, and as the lay and hook swing back, the bullion comes over the finger *r*, the hook is stopped with the point upward, and the finger *r* lifts the bullion off said hook.

The means for giving these motions will next be described.

The rail of the lay *b* carries the slide-bar *m*, upon which are mounted the bearings *5* for the shank of the hook *i*, and the parts that actuate it.

This slide-bar *m* is moved endwise at the proper time by the lever *n*, links *6* and *7*, lever *p*, and cam *q*, on the main shaft *e*, and the lever *n* is provided with a movable fulcrum, *8*, so that the end movement given to the slide *m* and hook *i* can be varied, and consequently the length of the bullion of the fringe increased or lessened.

Upon the slide *m* is a standard, *t*, that is guided by a bar, *9*, on the swords of the lay.

The shaft *s* that communicates a revolving motion to the hook *i*, through the wheel *10* and pinion *11*, is supported in bearings on *5* and *t*, and receives its motion from the wheel *u* and pinion *17*.

In order to rotate the wheel *u*, I connect therewith, by a pawl and ratchet, *12*, the barrel *v*, to which a cord or band, *13*, is applied, the same being wound around the barrel, and attached near the middle of the cord, and one end passes off to the spring *14*, and the other to the lever *w*; and from the other end of this lever *w* is a connection, *15*, to the lever *w'*, which receives motion at the proper time from the cam *16*, which is so shaped as to act upon the lever *w'*, press that down, swing the lever *w*, draw the cord *13*, and rotate the barrel *v*, wheel *u*, pinion *17*, shaft *s*, gear *10*, pinion *11*, and hook *i*, twisting the bullion at the time the shed has changed, and the loop of bullion-cord been beaten up by the lay *b* and reed *18*.

The ratchet and pawl *12* allow the barrel to be turned back by the spring *14* without rotating the other parts, and I remark that the fulcrum of the lever *w* is movable, so as to increase or lessen the motion of the cord *13*, and the consequent twisting of the bullion more or less, according to its length or character.

It is necessary that the hook *i* be stopped with the hook upward, so that the finger *r* may lift the bullion off the same. To do this, I provide stops *20* on the

shaft *s*, adjacent to the pinion 17, the parts being so proportioned that when either one of these stops 20 comes against the end of the pawl *o*, the hook *i* will be uppermost.

This pawl *o* is on a plate, 21, that has a stop to hold up the pawl *o*, the two swinging on the same centre.

Behind the standard *t* is a bent lever, 22, on a fulcrum, 23, and having a hinged dog, 24.

As the slide *m* is moved along, the dog 24 comes into contact with the pin 25 on the lay, and moves the lever 22, so as to depress the back end of the plate 21, and lift the pawl *o*, and retain it out of contact with the stops 20, and from the lever 22 a cord, 28, passes to the lever *w*, so that simultaneously with the final revolution of the hook *i*, by the movement of the lever *w*, the lever 22 is raised, so as to drop the pawl *o*, and arrest the movement of the parts, so that the hook *i* remains with its point uppermost.

The mode of actuating the finger *r* now alone remains to be described.

This finger *r* projects from the horizontal arm of a bent lever, 29, and the vertical arm is connected with the vertical arm of a similar lever, 30, and from the horizontal arm of this lever 30 a link, 31, connects to the lever 32, at the end of which is a tumbler-latch,

33, that is turned down by a projection, 34, on the lay *b*, as the same moves to beat up, but as the lay *b* goes back, this projection 34 takes this tumbler-latch 33, and the lever 32 is thereby depressed, and the parts moved to raise the finger *r*, and unhook the bullion from the hook *i*.

The warps forming the head of the fringe are to be of silk, or other suitable material, and those on the side from which the bullion projects are to be heavy threads or cords, for the purpose aforesaid.

What I claim, and desire to secure by Letters Patent, is—

1. The hook *i*, mounted upon the lay *b* and slide *m*, in combination with the mechanism, substantially as specified, for revolving said hook, and stopping the same in position for the bullion to be unhooked, substantially as set forth.

2. The finger *r*, mounted upon the bent lever 29, and actuated by the movement of the lay, substantially as set forth.

In witness whereof, I have hereunto set my signature, this 2d day of August, 1869.

GEORGE ROTH.
